UNITED STATES PATENT OFFICE

EVENCE COPPEÉ, OF BRUSSELS, BELGIUM.

REGENERATIVE COKE-OVEN.

1,267,380.

Specification of Letters Patent. Patented May 28, 1918.

Application filed July 28, 1914. Serial No. 853,603.

To all whom it may concern:

Be it known that I, EVENCE COPPEÉ, subject of the King of the Belgians, residing at 103 Boulevard de Waterloo, Brussels, Belgium, have invented a new and useful Improvement in Regenerative Coke-Ovens; and I do hereby declare the following to be a full, clear, and exact description of the same.

The different systems of regenerative coke ovens may be divided into two classes, according to which they comprise either a separate regenerator for each oven, or a common regenerator for the entire battery.

Both said arrangements have their inherent advantages and drawbacks. If on the one hand the arrangement of a single regenerator under all ovens of one and the same battery results in obtaining an automatic regulation of the working of the oven, through the uniform temperature of the hot air distributed into the different side walls, on the other hand said arrangement suppresses the independence which exists between the regenerators in the systems with a separate regenerator for each oven.

Said independence while advantageous in several respects gives rise to all the drawbacks inherent to said system, *i. e.* the mutual dependence of the ovens and of their respective regenerators, and the suppression of the automatic regulation of the working of the oven, which cannot be produced by separate regenerators, distributing the hot air at a density and a temperature that are obviously variable from one regenerator to the other.

The present invention has for its object a system of regenerative coke oven combining the advantages of both arrangements above described, as it insures the independence of the different regenerators while insuring at the same time the independence between each oven and regenerator, located beneath such oven, by means of an arrangement insuring uniform temperature of the hot air, or of the hot gases, or of the gas and air simultaneously, before their distribution in the different side walls.

It consists principally in that the combustion agent, the temperature of which is to be equalized, is collected at its outlet from the regenerators, into a mixing collecting flue

common to all regenerators, after which it passes into a distributing flue from which it is distributed to the ovens at a uniform temperature.

Figure 1 is a schematic view illustrating the principle of the invention.

Fig. 2 is a vertical longitudinal section taken through an oven, that is, a transverse vertical section through a bench of ovens and regenerators.

Fig. 3 is a horizontal section of the chimney and reversing valve.

Figs. 4, 5, and 6 are sectional views taken on the lines M—N, O—P, and R—S, respectively, of Fig. 2.

Fig. 7 is a schematic view illustrating a form of the invention in the case of ovens heated by means of blast-furnace gases or the like.

Fig. 8 is a vertical sectional view, showing the general arrangement of the several parts of the system illustrated in Fig. 7.

Fig. 9 is a sectional plan view of the chimney and of the reversing device.

Fig. 10 is a sectional view at right angles to Fig. 8, taken on the line X—Y of Fig. 8.

Referring to the embodiment shown in Figs. 1 to 6 inclusive:

It will be seen that each oven O of the bench of ovens is arranged above two regenerators, with regenerators of the R series below the ovens and at one side of the furnace and the regenerators of the R' series below the ovens and at the other side of the furnace.

The arrangement is such, as will now be described structurally, that either series of regenerators may have continuously passed therethrough, in parallel, the waste gases from the ovens, thereby to transfer and store a large amount of heat in the series, while passing the combustion agent, as air on its way to the ovens, through the other series previously heated as the first series is now being heated, thereby to preheat the air; the air being thus preheated also passing in parallel through its series; the arrangement being also such that the function of the two series, or the working of the apparatus, may be reversed at desired intervals.

The regenerators of the R series when acting as preheaters are adapted to be served

in parallel by a main air channel or conduit A, and the regenerators of the R_1 , when so acting, by a similar channel A'.

For the purposes of clarity, the passages 5 T and T' joining the conduits A and A' and the regenerators of the R and R' series, respectively, are omitted from Fig. 1.

The regenerators of the R series, when so acting as preheaters, are adapted to discharge in parallel into a collecting channel 10 or conduit B; the heated air passing thence through a passage K into a distributing channel or conduit C, and thence to the different sole-flues F.

15 These sole-flues are not indicated in Fig. 1; nor are there shown in Fig. 1, passages H leading from the individual regenerators of the R series to the collecting channel B of that series, or the passages U leading 20 from the distributing channel C to the sole-flues F.

The generators of the R_1 series are arranged so that they, too, when acting as preheaters, may discharge in parallel; they 25 then being served by elements A', B', C', K' and U', similar to the elements of A, B, K, C and U associated with the R regenerators.

It will be seen from a comparison of Figs. 2 and 6 that passages U' open into sole- 30 flues F'.

It will also be noted from Figs. 2 and 6 that similar valves t and t', h and h', and L and L', for the two series of regenerators R and R_1 are provided; although not shown 35 in Fig. 1.

Upon properly setting these valves and the valve W (Figs. 1 and 3), either of the 40 series of regenerators may have passed there-through the combustion agent to be heated, while the other series of regenerators has 45 passed therethrough the waste products of combustion from the ovens, and in either case any oven or any regenerator may be cut out from the others.

45 Selecting, for example, the regenerators of the R series, as the preheating regenerators, it will be seen from a comparison of Fig. 1 with Figs. 2, 4, and 6, that the heated air leaving the regenerator R_2 is discharged into 50 a common channel B with the air from the regenerator R_1 , and these airs are mixed. In the same way, the air leaving the regenerator R_3 will be mixed in this common channel with the air coming from R_1 and 55 R_2 ; and so on.

Thus, the air reaching the point a in the case of each conduit B allotted to each group of ovens, say twenty, of the plurality of groups comprising the apparatus, will be at 60 a temperature which is the average of that of all the regenerators discharging into that conduit. In this connection note that a conduit K is allotted in Fig. 1 to each group of twenty regenerators. This air arriving at 65 the point a, is drawn by suction into a dis-

tributing channel C, whence the hot air passes through passages U to the different sole-flues F, according to the proportions regulated by valves, L controlling the entrance of the air into said sole-flues F.

70 The arrangement described, on account of the mixing of the air coming from a whole series of regenerators, insures a uniform temperature for the hot air. This in turn insures a natural regulation of the working 75 of the battery. There is thus precluded any chance of the cooling of an oven. At the same time, any variation in the working of the battery is avoided, in contradistinction to the known systems of ovens with independent regenerators. Further, a total independence between the ovens and their regenerators is also obtained, by reason of which any oven may be put out of service without causing interruption in the service 80 of the corresponding regenerators, and any regenerator may be put out of service without necessitating extinction of the ovens above.

85 Referring now to Figs. 7 to 10, inclusive, there is shown an arrangement adapted to 90 permit the invention to be carried out when blast furnace gases or the like are used.

Here each series of regenerators is divided 95 into two kinds of regenerators, alternately arranged, whereby both the combustion agents may be preheated; the regenerators of the RG series (see Fig. 10) being for pre-heating the gas combustion agent, and the regenerators alternating with the RG 100 generators (see R_1 , R_2 , Fig. 10) being for preheating the air combustion agent.

As shown most clearly in Fig. 7, the incoming gases are passed through the channel A or A' and the channel D or D' and thence 105 led through the regenerators R or R' to enter the collecting channel C or C', the heated air is led off from the air regenerators on one side or the other of the apparatus, by way of a conduit or channel C or C' while 110 the heated gas is led off from the gas regenerators on that side of the apparatus by way of a conduit or channel D or D'. The channels B and C are connected by a passage K and the channels B' and C' are connected 115 by a passage K'.

As illustrated in Fig. 10, but not in Fig. 7, the gas regenerators of either series of regenerators on a side of the apparatus are connected to the channel D or D' by means 120 of passages X.

As indicated in Fig. 9, the gas channels D and D' are controlled at their inlet ends by valves V and V', branch conduits E and E' being provided as shown in Fig. 9. The 125 valves V and V', together with the valve W, are used for connecting the uptake Y to one side or the other of the apparatus to control the working thereof.

By properly adjusting valves W, V and 130

V' the gas regenerators as well as the air regenerators on either side of the apparatus, may be adapted for the heating of air. This is desirable when heating is by means of a rich gas. In such case the valve V and V' are permanently maintained open.

Having now described my invention, I declare that what I claim is:—

10 In a system of regenerative coke ovens, a series of regenerators, a plurality of ovens for which said regenerators are provided, a feed channel leading to the regenerators, said regenerators being disposed in parallel therewith, a collecting channel communicating with said regenerators whereby the dis-

charges therefrom will be successively brought together, an uptake, a plurality of sole-flues into one of which the heated body is discharged and from the other of which said body is drawn by suction to communicate with the uptake and means for reversing the action of the working.

20 In testimony whereof, I have signed my name to this specification in the presence of two subscribing witnesses.

EVENCE COPPEÉ.
